PAIR OF SUNGLASSES

Anthony Shindler, Brookline, Mass., assignor to American Optical Company, Southbridge, Mass., a voluntary association of Massachusetts

Filed June 14, 1965, Ser. No. 85,730

Term of patent 7 years

(Cl. D57—1)

FIG. 1 is a top plan view of a pair of sunglasses embodying my new design;

FIG. 2 is a front elevational view of the sunglasses shown in FIG. 1; and

FIG. 3 is a side elevational view thereof.

Portions of the temples have been broken away in FIG. 1 for convenience of illustration.

I claim:

The ornamental design for a pair of sunglasses, substantially as shown and described.
